UNITED STATES PATENT OFFICE

2,650,458

DISK EDGE DEBURRING MACHINE

Frank Charles Wallace, North Hollywood, Calif.,
assignor to Collins Radio Company, Cedar
Rapids, Iowa, a corporation of Iowa

Application April 24, 1952, Serial No. 284,099

2 Claims. (Cl. 51—103)

1

This invention relates in general to disc edge grinding means and in particular to apparatus for removing burrs from the outer edge of discs.

Mechanical filters made according to the principles disclosed in the co-pending patent application of Melvin L. Doelz entitled "Mechanical Filters," filed September 24, 1951, Serial Number 248,011, require a series of metal discs which serve as the frequency determining elements of the filters. The physical dimensions of such discs are quite critical. In construction of mechanical filters, according to the previously referenced Doelz application, applicant has found it desirable to produce discs by cutting them from rod stock of suitable material, as for example Nispan C which is a nickel alloy. Such cutting often-times leaves the discs with burrs about their outer peripheries which affect the frequency characteristics of the disc.

It is an object of this invention, therefore, to provide a disc edge deburring machine which will remove the rough edges from a plurality of discs.

Another object of this invention is to provide a disc edge deburring machine that will quickly finish the edges of a plurality of discs.

A feature of this invention is found in the provision for a pair of abrading wheels mounted adjacent each other and driven at different speeds with a plurality of discs held between the wheels by guide means.

Further objects, features and advantages of this invention will become apparent from the following description and claims when read in view of the drawings, in which:

Figure 1 is a top view of the disc edge deburring machine with the guide roller pivoted upwardly;

Figure 2 is a top view of the disc edge deburring machine with the guide member pivoted downwardly to the operating position; and

Figure 3 is a sectional view taken on line 3—3 of Figure 2.

Figure 1 shows a base plate 10 which has mounted thereon upwardly extending end plates 11 and 12. A first roller 13 of relatively large size is mounted between the end plates 11 and 12 on an axle 14. A driving gear 16 is attached to the axle 14 and meshes with a gear 17 connected to the output shaft of a suitable driving means, as for example an electric motor 18.

A second roller 19 is rotatably supported between the end plates 11 and 12 and is attached to an axle 21 which extends through the plate 12 and is connected to a gear 22 which is larger in size than the gear 16.

2

The gear 22 meshes with gear 17 and is driven by the motor 18. The roller 19 is smaller than the roller 13. The rollers 13 and 19 are covered with an abrasive material, as for example, emery cloth which is designated as 23 and 24, respectively, in Figure 3. The emery cloth may be glued to the rollers or attached in any other well known fashion.

Rotatably supported between the end plates 11 and 12, adjacent the rollers 13 and 19, is a guide means 26. The guide means 26 is supported on an axle 27 which has a lever arm 28 extending therefrom. A weight 29 is mounted to the outer end of arm 28.

As best shown in Figure 2, a pair of generally rectangular brackets 31 and 32 are rotatably supported adjacent each end on the axle 27 and a shaft 33 is rotatably supported between the outer end of the brackets 31 and 32 in suitable bearings. The brackets 31 and 32 are pivotally connected to the axle 27 so that the holding assembly may be moved relative to the rollers 13 and 19.

Slidably and rotatably mounted on the shaft 27 are a pair of brackets 34 and 36, respectively, which have knurled collars 37 and 38, respectively, attached thereto and fitted about the axle 27. The outer ends of the brackets 34 and 36 encompass the shaft 33. As best shown in Figure 3, the brackets 34 and 36 have downwardly extending projections 35 that extend below the axle 33 in the operating position.

A plurality of discs 39 are supported between the rollers 13 and 19.

In operation, the axle 33 is pivoted upwardly to the position shown in Figure 1 and a number of discs 39 which are to be deburred are placed in the valley between the rollers 13 and 19. The holding means is then pivoted to the position shown in Figure 2 and the knurled brackets 37 and 38 are pressed toward each other so as to hold the discs together.

The weight 29 applies a holding force to the axle 33 through the brackets 31 and 32. The motor is started and causes the rollers 13 and 19 to turn. The gearing as shown causes the rollers 13 and 19 to move in the same direction of rotation with the roller 13 traveling at approximately twice the angular velocity of the roller 19. It is this difference in angular velocity, as well as the difference in diameters of the rollers 13 and 19, which removes the burrs.

After a predetermined time the motor may be stopped and the lever arm 28 pivoted to the position shown in Figure 1 and the discs removed.

It is seen that this invention provides means for quickly and accurately deburring a plurality of discs while maintaining their symmetrical characteristics.

Although the invention has been described with respect to a preferred embodiment thereof, it is not to be so limited as changes and modifications may be made therein which are within the full intended scope of the invention, as defined by the appended claims.

I claim:

1. A disc edge grinding means comprising, a base plate, a pair of end plates attached to the base plate, a first roller rotatably supported between said end plates, a second roller rotatably supported between said end plates adjacent the first roller, a driving means geared to said first and second rollers to drive the first roller at approximately twice the angular rate of the second roller, said first roller having a diameter substantially twice that of the second roller, an axle pivotally supported between said end plates, a pair of brackets supported by said axle, a shaft supported between the free ends of said brackets, and a second pair of brackets slidably supported on said axle and said shaft and engageable with said plurality of discs to prevent them from moving longitudinally of said rollers.

2. A disc edge grinding means comprising, a base plate, a pair of end plates attached to the

base plate, a first roller rotatably supported between said end plates, a second roller rotatably supported between said end plates adjacent the first roller, a driving means geared to said first and second rollers to drive the first roller at approximately twice the angular rate of the second roller, said first roller having a diameter substantially twice that of the second roller, an axle pivotally supported between said end plates, a pair of brackets supported by said axle, a shaft supported between the free ends of said brackets, a second pair of brackets slidably supported on said axle and said shaft and engageable with said plurality of discs to prevent them from moving longitudinally of said rollers, a lever arm attached to said axle, and a weight attached to the end of said lever arm to bias it in one direction.

FRANK CHARLES WALLACE.
